Primary Examiner—A. Hugo Word*Assistant Examiner*—Celia Murphy*Attorney, Agent, or Firm*—Flehr Hohbach Test Albritton & Herbert**[57]****CLAIM**

The ornamental design for a handle assembly for micro-surgical instruments, as shown and described.

DESCRIPTION

FIG. 1 is a front perspective view of a handle assembly for micro-surgical instruments showing my new design;

FIG. 2 is a rear perspective view thereof;

FIG. 3 is a top plan view thereof;

FIG. 4 is a side elevational view thereof, both sides being identical;

FIG. 5 is a bottom plan view thereof;

FIG. 6 is a front elevational view thereof; and,

FIG. 7 is a rear elevational view thereof.

The broken lines showing the scissors element in FIGS. 1 through 6 are for illustrative purposes only and form no part of the claimed design.
